UNITED STATES PATENT OFFICE

GABRIEL MADLAND, OF CHICAGO, ILLINOIS, ASSIGNOR TO CAMEL COMPANY, A CORPORATION OF ILLINOIS

DOORCHECK MEANS

Application filed October 10, 1929. Serial No. 398,752.

This invention relates to side door construction.

The present invention relates more particularly to means for reducing or checking the speed of side doors for railway cars, known as box or house cars, when the doors approach the end of their travel.

It is a rule of the railroads that house cars are not to be shifted or started in transit unless the doors for said cars are latched. In spite of this rule trainmen frequently handle house cars in a careless manner, resulting in damage to the cars and consequent loss to the railroads, when movement of cars is begun without latching of the doors thereon. When the doors are in closed or partially closed position, sudden forward movement of the cars causes the doors to move rearwardly with such speed as to exert a great force of impact on the back stops for the doors. When it is considered that steel doors weigh between four hundred (400) and six hundred (600) pounds the force of this impact will be appreciated. As a consequence of the impact between the doors and their back stops the latter have frequently been sheared off the car, the door has been damaged and other serious injury has resulted.

This invention has for one of its objects, a construction whereby the above mentioned defects are obviated.

A further object is to provide means positioned on the car and on the door effective at the end of travel of the door, to check the movement thereof.

Another object is to provide checking means which may be easily fabricated, readily applied, and which are simple and efficient in operation.

A further object is the provision of a check or reducing means which may be readily attached to the existing car and door structures without necessitating modification of these structures.

It is also an object to provide a door checking means which will cause the door at the end of its movement to traverse an upward incline to reduce the speed of the door.

It is a further object to provide such means

which is readily applicable to both top and bottom hung sliding doors.

A further object is to provide a door supported for sliding movement on a plurality of rollers of different diameters, the rollers of smaller diameter being effective in checking the speed of the door.

A further object is to provide a hanger which is strong, compact, efficient in operation and easily made.

Further objects will appear as the description proceeds. In the accompanying drawings which illustrate a preferred embodiment of this invention and in which similar reference numerals refer to similar parts in the different views:

Figure 1 shows a partial elevational view of a car having a door mounted thereon, said door being shown in closed position and having applied thereto door checking means.

Figure 2 is a side elevational view, corresponding to Figure 1, but showing the door in open position and the door checking means in operative relation.

Figure 3 is a vertical sectional view taken on line 3—3 of Figure 1.

Figure 4 is a front elevation of the hanger for the door, looking at Figure 3 from the right.

Figure 5 is a sectional view on line 5—5 of Figure 3.

Figure 6 is a sectional view on line 6—6 of Figure 2.

Figure 7 is a modification, showing the application of the invention to a top supported door.

With reference to Figures 1 to 6 inclusive, the numeral 10 designates the side wall of a house car. A door opening 11 is provided in the side wall, said opening being adapted to be closed by a door 12. In its closed position the door is adapted to be fastened to the car by fastening means designated generally by the reference numeral 13. Supporting the door for horizontal sliding movement are a plurality of hangers 14, one hanger being secured adjacent each of the lower corners of the door. Each of these hangers is provided with a pair of rollers 15 and 16. The roller 15 is rotatably mounted on a pin 17, fixedly

secured in hubs 19 and 20, forming a part of the hanger. The roller 16, which is of less diameter than the roller 15, is rotatably mounted on a pin 18, secured in a hub 22, and in one wall of a housing 25, forming part of the hanger. It will be noted that the roller 15 is positioned between two relatively offset walls of the hanger so that, in effect, it is maintained within a housing 21 in said hanger. The hub 22, as well as the housing 25, is formed as part of a flange or plate depending from the housing 21. The pin 17 for the roller 15 is fastened to the hub 19 by means of a pin 26, while the pin 18 for the roller 16, is secured in position between the peened head 27 and shoulder 28, formed on said pin. Vertical ribs 24 are provided on the hangers for the purpose of lending additional strength thereto. The hangers are secured to the doors as indicated by means of rivets 30, which pass through holes 29 formed in the hangers.

The rollers 15 are adapted to travel on a main track 31. This track comprises a horizontal leg 32, which supports the roller directly and the vertical leg 33. The horizontal leg is provided with a downturned flange 34 adapted to coact with the inwardly and upwardly turned flanges 36 formed on the hanger. The track 31 is secured in position by means of rivets 38 passing through the vertical leg of said track and is supported on track brackets 35. Additional rivets 37 are used to secure the track brackets to the web 35 of a channel shaped sill member 43.

A supplemental track 39 is provided, which consists in the embodiment shown, of an angle member having one of its legs 42 positioned vertically and the other positioned horizontally. The supplemental track is supported in position by attachment to the vertical leg of the main track by means of the rivets 38 and shown in Figure 6 of the drawings. The horizontal leg 40 of the supplemental track has its upper surface inclined as shown at 41 in Figure 3 of the drawings.

Supported upon the horizontal leg 44 of the channel sill 43 is the flooring 46. This flooring projects somewhat beyond the web 50 of the sill and is protected by the horizontal portion 47 of a protecting plate which is downturned as indicated at 48, over the edge of the flooring. Door stops 49, 49', etc. are positioned as shown to prevent the door from leaving the track in its opening movement.

Figure 7 illustrates a modification of the invention. In this modification a top supported door is employed. This door is adapted to travel upon the horizontal leg 56 of the track 54. The track is secured through its vertical upstanding leg 55 to the vertical depending leg 52 of the Z shaped side plate 50 by rivets or the like 58. The web 53 of the side plate is positioned horizontally and the other leg 51 extends vertically opposite to

the leg 52. The door is supported for movement on the track 54 by means of a hanger 59. The hanger carries a roller 61, this roller being mounted upon a pin 62 fixed in the hanger. The hanger is fastened to the door by means of rivets 60. Positioned below the horizontal portion 56 of the track is a roller of smaller diameter than the roller 61. This roller 63 is secured to the hanger by means of the pin 64. Fastened to the vertically depending flange 57 of the track is a supplemental track 65. This track is positioned with one of its legs extending horizontally. The upper surface of this leg is inclined upwardly in the direction of the opening movement of the door in the same manner as the horizontal leg 40 of the track 39.

The supplemental rollers, together with the supplemental tracks, constitute the door checking means. The operation of this means will be made clear from the following:

Assuming the door to be in closed position, and desiring to open the door, the latch is released and the door moved toward the right in Figure 1 of the drawings. During the greater portion of this movement the door will be supported upon the main rollers 15. Normal movement of the door will continue upon the rollers 15 until the supplemental roller 16, carried by the hanger at the right of the door 12, comes into engagement with the supplemental track 39. Continued movement of the door will cause the roller 16 to ride up the inclined portion of the supplemental track. This movement of the roller 16 on the inclined portion causes the door and the main roller to be raised. The main rollers is now ineffective to support the door and the supplemental roller carries the door on the inclined track. The supplemental roller, however, is smaller in diameter than the main roller and this fact, together with the fact that the supplemental roller is riding up an inclined plane, will bring about a checking or reduction in the speed of the door. As a result of this, possibility of shearing of the back stops 49, 49', etc. with its attendant difficulties, will be obviated. While the reducing mechanism has been shown located so that it becomes effective in the opening movement of the door, it is apparent it may be employed so as to be effective in the closing movement of the door as well.

Although I have herein shown and described what I now consider the preferred manner of carrying out the invention, the same is merely illustrative, and I contemplate all changes and modifications that come within the scope of the claims appended hereto.

I claim:

1. Check means for the horizontally sliding door of a box car, said door being supported on a track by means of hangers provided with rollers, comprising an auxiliary roller provided on said door and an inclined

- portion provided on said track, the inclined portion comprising an angular member secured to the track and embodying a horizontal flange the upper surface of which is inclined, said auxiliary roller having engagement with the inclined portion of the track during a part of the movement of the door. 5
2. Check means for the horizontally sliding door of a house car, said door being supported on a track by means of hangers provided with rollers, comprising an auxiliary roller provided on said door and an inclined portion provided on the car, said inclined portion comprising a horizontal flange inclined upwardly in the direction of the opening movement of the door, said auxiliary roller and said inclined portion being adapted for engagement. 10
3. Check means for the horizontally sliding door of a house car, said door being supported on a track by means of hangers provided with rollers, comprising an auxiliary roller and an inclined portion provided on said track, said inclined portion comprising a horizontal flange secured to said track and positioned below the roller supporting part of the track, the upper surface of said flange being inclined upwardly in the direction of the opening movement of the door, said auxiliary roller and said horizontal flange adapted for engagement to check the speed of the door. 15
4. The combination with the door of a house car, the door being supported for horizontal sliding movement upon a main track by rollers carried by hangers secured to said door, of check means for said door, comprising a roller of smaller diameter than the supporting rollers and carried by said door adjacent to one of said supporting rollers, auxiliary track means secured to said main track and provided with an inclined portion, said smaller roller having engagement with said inclined portion of the auxiliary track 20
- 35 means for a part of the movement of the door, whereby to lift the door to disengage the said adjacent supporting roller from the main track and to support the door on the auxiliary track by the smaller roller. 40
5. A door for a house car, hangers secured to said door, housings on said hangers, main rollers mounted in said housings, a main track on which said rollers are adapted to travel, an additional roller mounted on one 45 of said hangers adjacent to its main roller, said additional roller being inoperative during the travel of the door on said adjacent main roller, a supplemental track, said additional roller having engagement with the supplemental track for a portion of the movement of the door, and said adjacent main roller being inoperative during such engagement. 50
6. A door for a house car, hangers secured to said door, housings on said hangers, main rollers mounted on said housings, a main track on which said rollers are adapted to travel, an additional roller mounted in one of said housings, said additional roller being inoperative during the travel of the door on said adjacent main roller, a supplemental track, said additional roller having engagement with the supplemental track for a portion of the movement of the door, and said adjacent main roller being inoperative during such engagement. 55
7. A door for a house car, hangers secured to said door, housings on said hangers, main rollers mounted on said housings, a main track on which said rollers are adapted to travel, an additional roller mounted on one of said hangers adjacent to a main roller, said additional roller being of smaller diameter than said main rollers and being inoperative during the travel of the door on the adjacent main roller, a supplemental track, said additional roller having engagement with the supplemental track for a portion of the movement of the door and the adjacent main roller being disengaged from said main track during such engagement of the additional roller. 60
8. A door for a house car, hangers secured to said door, housings on said hangers, main rollers mounted in said housings, a main track on which said rollers are adapted to travel, an additional roller mounted on one of said hangers adjacent to a main roller, said additional roller being inoperative during the travel of the door on the adjacent main roller, a supplemental track having a part thereof inclined, said additional roller having engagement with the inclined part of the supplemental track for a portion of the movement of the door, the adjacent main roller being rendered inoperative by such engagement. 65
9. A door for a house car, hangers secured to said door, housings on said hangers, rollers mounted in said housings, a main track on which said rollers travel for a portion of the movement of the door, additional rollers of smaller diameter than said former rollers mounted on said hangers, said additional rollers being inoperative during the travel of the door on the first mentioned rollers, a supplemental track having a part thereof inclined, one of said additional rollers having engagement with the inclined part of the supplemental track for a portion of the movement of the door, said engagement rendering one of the main rollers inoperative. 70
10. A door check for the horizontally sliding door of a railway car, comprising a hanger, said hanger being provided with a housing, a roller mounted in said housing, a plate depending from said housing, said plate being provided with a housing, a roller mounted in said second housing, and smaller in diameter than the roller in said first housing. 75
11. A door for a house car, hangers secured to said door, housings on said hangers, main rollers mounted on said housings, a main track on which said rollers are adapted to travel, an additional roller mounted in one of said housings, said additional roller being inoperative during the travel of the door on said adjacent main roller, a supplemental track, said additional roller having engagement with the supplemental track for a portion of the movement of the door, and said adjacent main roller being inoperative during such engagement. 80
12. A door for a house car, hangers secured to said door, housings on said hangers, main rollers mounted in said housings, a main track on which said rollers are adapted to travel, an additional roller mounted on one of said hangers adjacent to a main roller, said additional roller being of smaller diameter than said main rollers and being inoperative during the travel of the door on the adjacent main roller, a supplemental track, said additional roller having engagement with the supplemental track for a portion of the movement of the door and the adjacent main roller being disengaged from said main track during such engagement of the additional roller. 85
13. A door for a house car, hangers secured to said door, housings on said hangers, main rollers mounted in said housings, a main track on which said rollers are adapted to travel, an additional roller mounted on one of said hangers adjacent to a main roller, said additional roller being inoperative during the travel of the door on the adjacent main roller, a supplemental track having a part thereof inclined, said additional roller having engagement with the inclined part of the supplemental track for a portion of the movement of the door, the adjacent main roller being rendered inoperative by such engagement. 90
14. A door for a house car, hangers secured to said door, housings on said hangers, rollers mounted in said housings, a main track on which said rollers travel for a portion of the movement of the door, additional rollers of smaller diameter than said former rollers mounted on said hangers, said additional rollers being inoperative during the travel of the door on the first mentioned rollers, a supplemental track having a part thereof inclined, one of said additional rollers having engagement with the inclined part of the supplemental track for a portion of the movement of the door, said engagement rendering one of the main rollers inoperative. 95
15. A door for a house car, hangers secured to said door, housings on said hangers, main rollers mounted in said housings, a main track on which said rollers are adapted to travel, an additional roller mounted in one of said housings, said additional roller being inoperative during the travel of the door on said adjacent main roller, a supplemental track, said additional roller having engagement with the supplemental track for a portion of the movement of the door, and said adjacent main roller being inoperative during such engagement. 100
16. A door for a house car, hangers secured to said door, housings on said hangers, main rollers mounted in said housings, a main track on which said rollers are adapted to travel, an additional roller mounted in one of said hangers adjacent to a main roller, said additional roller being of smaller diameter than said main rollers and being inoperative during the travel of the door on the adjacent main roller, a supplemental track, said additional roller having engagement with the supplemental track for a portion of the movement of the door and the adjacent main roller being disengaged from said main track during such engagement of the additional roller. 105
17. A door for a house car, hangers secured to said door, housings on said hangers, rollers mounted in said housings, a main track on which said rollers travel for a portion of the movement of the door, additional rollers of smaller diameter than said former rollers mounted on said hangers, said additional rollers being inoperative during the travel of the door on the first mentioned rollers, a supplemental track having a part thereof inclined, one of said additional rollers having engagement with the inclined part of the supplemental track for a portion of the movement of the door, said engagement rendering one of the main rollers inoperative. 110
18. A door for a house car, hangers secured to said door, housings on said hangers, main rollers mounted in said housings, a main track on which said rollers are adapted to travel, an additional roller mounted in one of said hangers adjacent to a main roller, said additional roller being inoperative during the travel of the door on the adjacent main roller, a supplemental track, said additional roller having engagement with the supplemental track for a portion of the movement of the door, and said adjacent main roller being inoperative during such engagement. 115
19. A door for a house car, hangers secured to said door, housings on said hangers, main rollers mounted in said housings, a main track on which said rollers are adapted to travel, an additional roller mounted in one of said hangers adjacent to a main roller, said additional roller being of smaller diameter than said main rollers and being inoperative during the travel of the door on the adjacent main roller, a supplemental track, said additional roller having engagement with the supplemental track for a portion of the movement of the door and the adjacent main roller being disengaged from said main track during such engagement of the additional roller. 120
20. A door for a house car, hangers secured to said door, housings on said hangers, main rollers mounted in said housings, a main track on which said rollers are adapted to travel, an additional roller mounted in one of said hangers adjacent to a main roller, said additional roller being inoperative during the travel of the door on the adjacent main roller, a supplemental track, said additional roller having engagement with the supplemental track for a portion of the movement of the door, and said adjacent main roller being inoperative during such engagement. 125
21. A door for a house car, hangers secured to said door, housings on said hangers, main rollers mounted in said housings, a main track on which said rollers are adapted to travel, an additional roller mounted in one of said hangers adjacent to a main roller, said additional roller being of smaller diameter than said main rollers and being inoperative during the travel of the door on the adjacent main roller, a supplemental track, said additional roller having engagement with the supplemental track for a portion of the movement of the door and the adjacent main roller being disengaged from said main track during such engagement of the additional roller. 130

ameter than said first mentioned roller, and an upwardly inclined, elongated member adapted for engagement with said smaller roller.

- 5 11. A check for the horizontally sliding door of a railway car comprising rolling means carried by said door, said rolling means being inoperative for a portion of the travel of the door, and means mounted on 10 said car having an inclined member, said rolling means having operative engagement with said inclined member adjacent the fully open position of said door to reduce the speed thereof.
- 15 Signed at Chicago, in the county of Cook and State of Illinois, this 8th day of October, 1929.
